ANTI-SPLASH VESSEL FOR LIQUIDS

Cecil S. Robinson, Englewood, N. J., assignor to Robinson Aviation, Inc., Teterboro, N. J., a corporation of New York

Application June 5, 1956, Serial No. 589,473

4 Claims. (Cl. 220—90.4)

The present invention relates to an anti-splash vessel such as a drinking cup or other normally open-topped receptacle for liquids which is particularly useful in restaurants where filled vessels must be carried or in airplanes, trains and ships. Efforts have been made in the past to provide drinking cups, for example, which tend to prevent splashing of the liquid contents but the structures thus produced have been either insufficiently effective or have presented unusual contours to the lips of the user and in many cases have suffered both defects. In many cases the modifications of conventional design which are adopted to reduce splashing make the vessel difficult or impossible to clean or stack and increase the cost of manufacture beyond practical limits.

It is an object of this invention to provide a vessel of the type described which is unusually effective and at the same time presents a familiar contour to the lips of the user, is easily cleaned, may be securely stacked and which may be manufactured with little increase in cost. Other and further objects will appear from a consideration of a preferred form of the present invention taken in connection with the drawings forming a part of this specification.

Briefly described the present invention provides a baffle ring of particular contour which projects inwardly of the vessel at a level sufficiently below the rim of the vessel to avoid contact, under normal conditions, with the lips of the user when the present invention is embodied in a drinking vessel. The walls of the vessel both above and below the baffle ring may have the gently, outwardly flared contour which appears to be preferred by users although such walls may be substantially vertical or inwardly converging if so desired. For the purposes of the present invention the rim of the vessel need not have any unusual contour since the particular contour of the baffle ring is responsible for the effectiveness of the present invention.

In the drawings:

Fig. 1 is a top plan view of a drinking cup embodying the present invention;

Fig. 2 is a vertical section taken along the line 2—2 in Fig. 1; and

Fig. 3 is a view similar to Fig. 2 but showing a second drinking cup of identical construction in stacked relation with the one shown in section.

Referring now to the drawings, the invention is shown embodied in a drinking cup although it will be understood that the principles of the present invention are equally applicable to vessels of various types for containing liquids. The cup is generally indicated by the reference numeral 10 and it comprises a bowl-shaped body having a conventional handle 12 which may be integral with the body. The cup may be made of ceramic or plastic material, as desired, and it is a particular feature of the present invention that the special construction provided for reduction of splashing may be incorporated as an integral part of the cup without presenting

2

any great difficulty in molding thereof in accordance with conventional practice. It will be noted that the cup includes a bottom 14 and an outwardly flaring side wall portion 16. The contour of the side wall portion 16 is interrupted by a baffle ring 18 above which is located a side wall portion 20 which may flare outwardly at any desired and conventional angle. The side wall portion 20 terminates in a smoothly rounded rim or lip 22. It is contemplated that the outward flare of the wall portion 20 as well as the thickness thereof and the contour of the rim 22 shall be quite conventional so that the user of the cup will not be confronted with some unusual angle, contour or thickness.

The baffle ring 18 extends inwardly of the cup so as to form an annular body of substantially triangular cross-section. The specific contour or slope of the upper surface 24 of the baffle ring is not critical insofar as the anti-splash function of the baffle ring is concerned. For other purposes to be described below, it may be desirable to form the upper surface 24 as a section of a cone. In any event, the upper surface should be smoothly rounded into the surface of the wall portion 20 and preferably should slope downwardly to avoid trapping of liquid and so as to present no difficulty in cleaning.

The contour and distance of inward projection of the lower surface 26 of the baffle ring 18 is critical to the accomplishment of desired results. Thus, the surface 26 is curved smoothly from the surface of the wall portion 16 inwardly of the cup, the curvature being such as to

deflect any up-surging liquid into a path such that the liquid will fall back into the cup. To this end, the curvature should be such as to include a portion, a tangent to which lies at a relatively small angle with respect to the horizontal as viewed in Fig. 2. Thus the lines 28 and 30

which are tangent to the portion of the curve 26 lying innermost of the cup are at an angle of about 20° to 30° with the horizontal. Expressed otherwise, the lines 28 and 30 intersect the axis 31 of the cup at an angle of about 60° to 70°. It will be understood that liquid surging up the walls 16 will be deflected by the curved portion 26 so as to tend, after leaving the curved portion 26, to continue in a straight line corresponding with the tangents 28 and 30. Having been deflected to a path so close to the horizontal the liquid will tend to fall back into the vessel without splashing over the rim.

With respect to the contour of the baffle ring 18, it should further be pointed out that it must project inwardly of the cup for a substantial distance whereby the curve 26 will deflect a substantial volume of liquid. Such volume should be sufficient to overcome any tendency of other portions of the liquid toward splashing vertically from regions within the central part of the cup. It has been found that there is a definite relationship between the extent of inward projection of the baffle ring 18 and the diameter of the vessel. Thus, the horizontal distance from line a to line b (Fig. 2) or from line c to line d should be equal to from about 5% to about 8% of the diameter of the vessel as measured between the lines a and d. From a consideration of Fig. 2, it will be apparent that the distance from line a to line b, for example, represents the actual extent of inward projection of the baffle ring 18, measured from the point at which the curved surface 26 intersects the uppermost part of the surface 16.

With regard to the limits just set forth, it will be understood that the effectiveness achieved can be assessed only on a practical basis whether the tests be conducted under actual or simulated conditions. For example, a coffee cup with a baffle ring having curvature and size within these limits has been found to effectively prevent splashing of its liquid content when carried in a tray or used

by a passenger in an aircraft flying in weather sufficiently rough to be definitely uncomfortable to those accustomed to travel by air. Thus, the present invention makes it possible to safely serve beverages in a cup of apparently familiar design and contour on aircraft, railroad dining cars and the like, under conditions formerly regarded as impossible or as requiring the use of partially filled tumbler-shaped vessels or other makeshifts.

The baffle ring 18 may be made to project inwardly more than the 8% upper limit above set forth but such increase is not accompanied by any demonstrable increase in effectiveness. Similarly, the angle between the lines 28 and 30 and the axis 31 of the vessel may be increased to 80° or more without noticeable improvement. However, the minimum limits cannot be substantially reduced without rendering the baffle ring 18 much less effective. There are further and practical reasons for not increasing the limits. If the lines 28 and 30 were more nearly horizontal or if the curve 26 were to be made reentrant the vessel would be very difficult to clean and would not tend to drain dry upon inversion. If the baffle ring 18 were to project inwardly for a substantially greater distance, it would present similar difficulties in cleaning and would further complicate moulding.

It is preferred to make the baffle ring 18 discontinuous by providing notches 32 and 34 which are diametrically opposed on a diameter 36 at right angles to the diameter 38 extending through the handle 12. These notches will facilitate draining of the vessel by right-handed and left-handed users, respectively.

It has been stated above that the contour of the upper surface 24 of the baffle ring 18 is not critical. However, such surface should incline downwardly at an angle sufficient to permit ready draining of liquid therefrom. This will facilitate cleaning and drying and also will prevent unsightly accumulation of liquid while the cup is in use. It is preferred to make the upper surface as a section of a cone and to provide a mating conical section 40 on the exterior of each vessel of the same set so that they may be firmly stacked as shown in Fig. 3.

The baffle ring 18 may also serve as a convenient indicator for uniform filling of the cups. For example, they may be filled to a level coinciding with the inner edge of the baffle ring 18 with assurance that they may be carried and used without danger of spilling under very adverse conditions.

I claim:

1. An anti-splash drinking vessel for liquids comprising a bottom, an upwardly extending outwardly sloping side wall, a rim, and a baffle ring extending substantially continuously around the inner circumference of said vessel and radially inwardly thereof substantially parallel with said rim, said baffle ring being positioned below said rim a distance sufficient but not substantially exceeding the minimum distance required to avoid contact between the said baffle ring and the lips of a person drinking from said vessel, said baffle ring being generally triangular in cross-section and having a lower surface which is inclined upwardly to the inner edge thereof and curved smoothly inwardly from the side wall of said vessel to form a radially inner portion thereof which forms a substantial angle with the horizontal said angle being small as compared to the angle formed by the tangent to said radially inner portion at the point of the intersection of the tangent with the vertical central axis of said vessel above said baffle ring, and said baffle ring having an upper surface which slopes inwardly and downwardly of said vessel.

2. An anti-splash drinking vessel for liquids comprising a bottom, an upwardly extending outwardly sloping side wall, a rim, and a baffle ring extending substantially continuously around the inner circumference of said vessel and radially inwardly thereof substantially parallel with said rim, said baffle ring being positioned below said rim a distance sufficient but not substantially exceeding the

minimum distance required to avoid contact between the said baffle ring and the lips of a person drinking from said vessel, said baffle ring being generally triangular in cross-section and having a lower surface which is inclined upwardly to the inner edge thereof and curved smoothly inwardly from the side wall of said vessel to form a radially inner portion thereof which forms a substantial angle with the horizontal said angle being small as compared to the angle formed by the tangent to said radially inner portion at the point of the intersection of the tangent with the vertical central axis of said vessel above said baffle ring, the outer diameter of approximately the lower half of said vessel being less than the inner diameter of said baffle ring whereby a major portion of one of said vessels is nestable within another, and said baffle ring having an upper surface which slopes inwardly and downwardly of said vessel.

3. An anti-splash drinking cup for liquids comprising a bottom, an upwardly extending outwardly sloping side wall, a rim, and a baffle ring extending substantially continuously around the inner circumference of said vessel and radially inwardly thereof substantially parallel with said rim, said baffle ring being positioned below said rim a distance sufficient but not substantially exceeding the minimum distance required to avoid contact between the said baffle ring and the lips of a person drinking from said vessel, said baffle ring being generally triangular in cross-section and having a lower surface which is inclined upwardly to the inner edge thereof and curved smoothly inwardly from the side wall of said vessel to form a radially inner portion thereof which forms a substantial angle with the horizontal said angle being small as compared to the angle formed by the tangent to said radially inner portion at the point of the intersection of the tangent with the vertical central axis of said vessel above said baffle ring, said tangent intersecting said axis at said point at an angle of from about 60° to about 70°, said baffle ring extending inwardly of said vessel for a distance equal to from about 5% to about 8% of the diameter of said vessel at the point of intersection of said lower surface with the inner surface of said side wall, the outer diameter of approximately the lower half of said vessel being less than the inner diameter of said baffle ring whereby a major portion of one of said vessels is nestable within another, and said baffle ring having an upper surface which slopes inwardly and downwardly of said vessel.

4. An anti-splash drinking cup for liquids comprising a bottom, an upwardly extending outwardly sloping side wall, a rim, a radially extending handle adjacent to said rim and a baffle ring extending substantially continuously around the inner circumference of said vessel and radially inwardly thereof substantially parallel with said rim, said baffle ring being positioned below said rim a distance sufficient but not substantially exceeding the minimum distance required to avoid contact between the said baffle ring and the lips of a person drinking from said vessel, said baffle ring being generally triangular in cross-section and having a lower surface which is inclined upwardly to the inner edge thereof and curved smoothly inwardly from the side wall of said vessel to form a radially inner portion thereof which forms a substantial angle with the horizontal said angle being small as compared to the angle formed by the tangent to said radially inner portion at the point of the intersection of the tangent with the vertical central axis of said vessel above said baffle ring, said tangent intersecting said axis at said point at an angle of from about 60° to about 70°, said baffle ring extending inwardly of said vessel for a distance equal to from about 5% to about 8% of the diameter of said vessel at the point of intersection of said lower surface with the inner surface of said side wall, the outer diameter of approximately the lower half of said vessel being less than the inner diameter of said baffle ring whereby a major portion of one of said vessels is nestable within another, said baffle ring having an upper surface which

slopes inwardly and downwardly of said vessel, said baffle ring having formed therein a pair of notches extending transversely of said baffle ring and diametrically opposed on a diameter of said cup which is approximately at right angles to the radial axis of said handle, and said notches having bottoms coinciding substantially with the inner surface of said side wall to facilitate draining of said cup by a user.
